ABSTRACT OF THE DISCLOSURE

Headgear for use in a game involving blows between adversaries to indicate a point or win. A frame to protect the head of a contestant has mounted on it a pin slideable under impact to release a visor which drops over the front of the frame to cut off the view of the wearer.

The present invention relates to a game apparatus and more particularly to headgear for use by participants in a game of physical contact involving blows between adversaries.

In contests involving physical contact between competitors the desired end is to defeat the opponent. Since it is not desirable to do physical harm in order to demonstrate this desired end, indicator means are sometimes adopted to record a point or a win. Contests in which blows are dealt to an adversary by use of a mace or like means are not undertaken because of lack of suitable indicator means.

It is an object of the present invention to provide apparatus, for use in a game of physical contact between adversaries involving blows, with which a point or win may be indicated without injury to the losing contestant.

An example embodiment of the invention is illustrated in the accompanying drawings in which:

FIGURE 1 is a view in perspective of the headgear mounted on a contestant's head;

FIGURE 2 is a side view of a mallet for use by each contestant; and

FIGURE 3 is a planar cross-sectional view taken along the line 3—3 of FIGURE 1.

The headgear of the invention as seen in the drawings consists of a unitary frame 10 having a transversely concave vertical faceguard 11 and a flat horizontal cap plate 12 at right angles to the faceguard. A pair of spaced bosses 13 are fixed to the top or outer surface of cap plate 12. A pin 14 mounted in bosses 13 is freely slideable therein. Pin 14 carries a head 15 at its rearward end and is held in bosses 13 by a pair of washers 16 of rubber or the like, one washer being fixed to each boss by bolts 16a. Pin 14 is frictionally gripped by washers 16 but is forcibly slideable in the washers under longitudinal impact force. Free end 14a of pin 14, opposite head 15, projects forwardly with respect to the plane of faceguard 11 when head 15 is bearing against adjacent washer 16.

Faceguard 11 has a plurality of horizontal slots or apertures 17 which form a grille for viewing through the faceguard. Along each side edge 11a of faceguard 11 is a shoulder 18 providing an inwardly directed groove 19. A transversely concave visor plate 20 concentric with faceguard 11 slides vertically in grooves 19. When in its lowered position, lower edge 21 of visor 20 rests on an outwardly projecting lip 22 fixed on the outer surface of faceguard 11 below apertures 17 and the visor covers the apertures. An aperture 23 is located centrally in visor plate 20 adjacent its upper edge 24 and receives the free

2

end 14a of pin 14 when the pin projects forwardly with respect to the plane of faceguard 11, thus holding the visor in an upper position on the faceguard and exposing apertures 17 to give the wearer a view through the faceguard.

A resilient pad or cushion 25, of foam rubber or other suitable material, contoured to rest upon the crown of the wearer's head, is fixed to the bottom or inner surface of cap plate 12. Attached to faceguard 11 on its inside surface adjacent its lower end 11b is a second resilient pad 26 contoured to receive the chin of the wearer. A pair of buckle straps 27 and 28 are attached to side edges 11a of faceguard 11 and are positioned to engage the back of the wearer's head and neck respectively, thus securing frame 10 to the head.

In the operation of the device each adversary fits a frame 10 to his head by resting pad 25 on top of his head, placing pad 26 beneath his chin and buckling straps 27 and 28 about his head and neck respectively. Visor 20 is raised and pin 14 is forced forwardly through washer 16 to engage aperture 23 in the visor and hold the visor in its upper position exposing apertures 17 through which the contestant views his opponent. Each contestant possesses a mallet 29 such as that shown in FIGURE 2 of the drawings having a head 30, of suitable material such as plastic, fixed to a rigid shaft or handle 31. With mallet 29 each contestant tries to strike end 14a of pin 14 mounted on frame 10 of his adversary to drive the pin axially rearwardly through bosses 13 and washers 16. When pin 14 is driven rearwardly, in the direction shown by arrow 33 in FIGURE 3 of the drawings, a distance sufficient to clear end 14a from aperture 23, visor 20 is released and drops over apertures 17, as indicated by arrow 34, the visor being guided by slots 19 and arrested by stop 22. This movement of visor 20 cuts off the view of the contestant and signifies a point or game won by his opponent.

It will be appreciated that the difficulty or ease of driving pin 14 rearwardly through bosses 13 and washers 16 is governed by frictional resistance imparted by the washers to the pin. Thus by use of appropriate washers 16, visor 20 may be released by a single blow or by repeated blows against pin 14.

I claim:

1. Headgear, for use by a contestant in a game involving blows between adversaries, comprising: a frame supportable by the head of said contestant and adapted to protect said head against impact by said blows; an axially slideable pin mounted on the frame and having one end thereof exposed to receive said impact; and means engaged by the pin when in an initial position and actuatable on slideable movement of the pin under said impact to obstruct the view of the contestant.

2. Apparatus as claimed in claim 1 in which the frame comprises a face guard and a cap plate, the face guard having viewing apertures closable by the view obstructing means.

3. Apparatus as claimed in claim 2 in which the cap plate carries on its lower surface shock absorbent material adapted to rest on the head of the contestant and the face guard carries adjacent its lower edge a chin rest of shock-absorbent material.

4. Apparatus as claimed in claim 2 in which the slideable pin is mounted on the cap plate and projects forwardly of the face guard, the view obstructing means comprising a visor engaged by the pin and releasable by

3,456,947

3

predetermined movement of the pin to obstruct the view through apertures in the face guard; the frame carrying shock-absorbent means adapted to rest against the head of the contestant.

5. Apparatus as claimed in claim 4 in which the visor carries an aperture adjacent its upper edge, the pin being slidably mounted axially in bosses fixed to the cap plate and engaging the aperture when in a forward position.
